UNITED STATES PATENT OFFICE.

HUBERT W. C. BRUSHWOOD, OF DENVER, COLORADO.

FASTENER FOR HALF-SOLES.

1,290,068.

Specification of Letters Patent.

Patented Jan. 7, 1919.

Application filed October 8, 1917. Serial No. 195,260.

To all whom it may concern:

Be it known that I, HUBERT W. C. BRUSHWOOD, a citizen of the United States, residing at the city and county of Denver, and State of Colorado, have invented certain new and useful Improvements in Fasteners for Half-Soles; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to fasteners for half soles for boots and shoes, my object being to provide a device of such character that any one may quickly apply a half sole to a boot or shoe, thus obviating the expense and delay incident to going to a shoe-maker in order to have the half sole secured by sewing or nailing, as has heretofore been practised. Furthermore, my improvement not only secures the half sole in place without the use 25 of nails or stitches, but it also protects the half sole as well as the main sole of the shoe.

Generally speaking, the device consists of a spring member adapted to engage and fit 30 the sole of a boot or shoe after the half sole has been applied thereto. It engages the edge of the sole and is fastened at the rear by an adjustable device of any suitable character. It has sufficient yielding capacity so

35 that it may be opened sufficiently to readily engage the sole on opposite sides and allow the lateral projections with which it is equipped, to engage the crease or groove of the boot or shoe between the upper and 40 the sole, whereby the fastener is prevented from slipping from the sole. The device is also equipped with projections which engage the half sole from below, thus securely connecting the half sole to the boot or shoe after

45 the extremities of the spring member are connected in the rear as by a turn buckle device or a nut having right and left threaded recesses which coöperate with similarly threaded studs with which the opposite extremities of the article are respectively provided.

In order to allow the sole of the shoe the necessary flexibility and obviate stiffness, the fastener is provided on each side with parts 55 of such shape that they will readily bend at

the part of the sole where the necessity for bending or yielding is greatest.

Having briefly outlined my improvement I will proceed to describe the same in detail, reference being made to the accompanying drawing, in which is illustrated an embodiment thereof. In this drawing:

Fig. 1 is a perspective view of a shoe equipped with my improvement.

Fig. 2 is a bottom plan view of the same. 65

Fig. 3 is a top plan view of the device shown in detail and on a larger scale. This is a view looking in the direction of arrows 3, Fig. 4.

Fig. 4 is a side elevation of the device, or 70 a view looking in the direction of arrows 4, Fig. 3, the bending or yielding capacity of the device being indicated by dotted lines.

Fig. 5 is a cross section taken on the line 5—5, Fig. 4 looking toward the left. 75

The same reference characters indicate the same parts in all the views.

Let the numeral 5 designate my improved device considered in its entirety and consisting preferably of a thin piece of sheet steel 80 6 which is of a depth approximately the same as the thickness of the sole of the boot or shoe when the half sole is applied except that a part 7 located approximately at the ball of the shoe when applied, is given a cylindrical or wire shape as distinguished from the flat, vertically disposed shape of the body of the device. It is well known that sheet metal though exceedingly thin, if of any considerable width will not bend edgewise 85 to any appreciable extent, hence the necessity for the part 7 in order to give the necessary flexibility to the sole of the shoe at the ball of the foot when my improvement is in use. It is intended that the device shall be 90 very thin and, therefore, light in weight, though in the drawing the thickness is somewhat exaggerated in order to facilitate clearness of illustration. 95

The thin, flat, yielding part 6 of my improvement is provided at both the top and bottom edges with inward projections, designated 8 and 9, respectively, the top projections 8 engaging the sole from above while the bottom projections 9 engage the 100 half sole from below. The rear extremities of the yielding device are reinforced to form lugs 10 of suitable mass, these lugs being provided with inwardly projecting threaded studs 12 which engage and coöperate with 105 110

right and left threaded recesses formed in a rotary member 13 which is provided with openings 14, in which a small nail or other suitable device may be inserted for the purpose of tightening the fastener upon the shoe, after the half sole has been applied. It will be understood that the extremities of the device may be connected for locking purposes in any other suitable or convenient manner, as by the employment of a key after the manner of fastening skates.

From the foregoing description, the use of my improved device will be readily understood. In order to secure a half sole to the boot or shoe, it is only necessary to put the half sole in position, then bend the article 5 outwardly on opposite sides sufficiently to allow the projections 8 and 9 to engage the sole above and the half sole below, after which the device is tightened on the shoe by rotating the part 13, whereby the two lugs 10 are caused to approach each other until the desired degree of security is obtained. It will be understood that when the half sole is fastened by means of my improvement, the sole may bend at the ball of the foot by reason of the shape and location of the parts 7, whose function is to give the necessary flexibility, as heretofore explained.

Attention is called to the fact that instead of forming the device of spring metal or yielding material whereby it has sufficient spring capacity, to allow it to open and close for attaching and detaching purposes, it may if desired be hinged at the front to permit the opening and closing action, though it is believed preferable to form the device of spring metal, of such character that a hinge joint will not be necessary.

Having thus described my invention, what I claim is:

1. A fastener for half soles comprising a thin metal band with a plurality of lugs at

its top and bottom edges, the said band being adapted to engage the exposed vertical edges of the sole and half sole, and means for connecting the extremities of the band in the rear. 45

2. A fastener for half soles comprising a thin metal band with a plurality of lugs at its top and bottom edges, the said band being adapted to engage the exposed vertical edges of the sole and half sole, and means for connecting the extremities of the band in the rear, the part of the band adjacent the ball of the shoe being shaped to yield vertically to the plane of the device as a whole, to permit the necessary flexibility of the sole while walking. 50

3. A fastener for securing a half sole to the sole of a shoe comprising a flexible metal band adapted to engage the edges of the sole and half sole and of approximately the same length and shape as the half sole, and projections on the edges of the band adapted to engage the opposite faces of the sole and half sole adjacent their edges to secure the two together, the fastener being expansible throughout its length, whereby the side portions thereof may be separated bodily from each other for attaching or detaching. 55

4. A fastener for securing a half sole to the sole of a shoe comprising a flexible metal band adapted to engage the edges of the sole and half sole, and of approximately the same length and shape as the half sole, and a plurality of lugs on the edges of the band adapted to engage the opposite faces of the sole and half sole adjacent their edges to secure the two together, the side portions of the fastener adjacent the ball of the shoe having parts which are rounded in order to yield vertically to the plane of the device as a whole and permit the necessary flexibility of the sole and half sole. 60

In testimony whereof I affix my signature.

HUBERT W. C. BRUSHWOOD.
